UNITED STATES PATENT OFFICE.

JAMES DELOS NEGUS, OF DOUGLAS, WYOMING.

RAILWAY-TRACK CONSTRUCTION.

1,299,760.

Specification of Letters Patent.

Patented Apr. 8, 1919.

Application filed June 22, 1918. Serial No. 241,335.

To all whom it may concern:

Be it known that I, JAMES D. NEGUS, a citizen of the United States, residing at Douglas, in the county of Converse and State of Wyoming, have invented certain new and useful Improvements in Railway-Track Construction, of which the following is a specification.

The invention relates to improvements in the construction of railway tracks, the object of the invention being to prevent, what is usually termed "the creeping of rails" in the tracks, and which results in the tracks becoming unstable, insecure and dangerous, and requires large expense for readjustment of the rails to maintain them in proper position and alinement so that traffic can be maintained with the utmost attainable safety, at low cost. The so called "creeping of rails" in tracks, is caused mainly by the inequalities in the material of which the road-beds are composed and the somewhat unstable, loose, disconnected elements therein; especially when the road bed materials are made soft by the presence of water therein. Under such conditions, the ties supporting the rails are unstable and do not furnish as good support for the rails as should be provided. Creeping of the rails is caused by what is usually referred to as "wave action", which is almost entirely due to the causes above mentioned, and the result is to subject the rails, cross-ties, and all the elements composing the ordinary railway tracks and the supporting materials thereunder, to undue and unnecessary strains which cause breakages, disasters, wrecks and the consequent loss of human lives and destruction of property, increasing the cost of transportation on the railways and decreasing the profits and benefits arising from the construction and operation of railways under present existing conditions.

The object of the invention is to provide a railway track structure which will reduce the cost of repairs and the wear upon the metal rails, and the strain and wear upon the cross-ties, and will prevent relative lateral or longitudinal movement in any direction between the rails and the ties and thereby maintain the proper alinement of the rails and the proper grade to prevent derailments

and other accidents, and will stabilize and reinforce the whole track structure and the materials supporting them, so that trains can be operated thereon with safety and at reduced cost to the owners of the railways and the patrons thereof.

With these objects and other objects in view, the invention consists of the features of construction, combination and arrangement of parts hereinafter fully described and claimed; reference being had to the accompanying drawings in which:

Figure 1 represents a top plan view of a section of a track with devices embodying my invention in position thereon.

Fig. 2 is a side elevation of the same.

Fig. 3 is a vertical section taken substantially on line 3—3 of Fig. 1. 70

Fig. 4 is a vertical section taken substantially on line 4—4 of Fig. 1.

Fig. 5 is a detail section and plan taken substantially on line 5—5 of Fig. 3.

Referring now to the drawings, the numeral 10 designates the rail and the numeral 11 designates the tie, and for the purpose of convenience, the numeral 11' is used to designate each of a pair of ties on each side of a central tie 11, forming a group of three adjacent ties. The track composed of these rails and ties is preferably embedded in good dry material that is coherent, as far as possible, so as to offer the greatest resistance to all movements of the ties in any direction out of their proper place. Where the supporting material or ballast in which the ties are embedded is of light unstable character, it will perhaps be advisable to specially reinforce the ties by embedding them in hydraulic cement, so as to increase the area of their outer surface and thereby enlarge the area of the material against which the ties impinge. These ties 11 and 11' are of wood, or any other suitable material. 95

I form in the base of the rail 10 the opening or aperture 12 and place in this opening or aperture 12 the sleeve or washer element 13. This hole or aperture 12 in the base of the rail is placed in alinement or registration with the socket or opening 14 which is drilled into the tie 11 to receive the elongated pin or bolt 15 which is of the form shown, being preferably threadless and

headless, but of sufficient length to extend a suitable distance above the base of the rail, as clearly shown in the drawings. In order to properly anchor this pin or bolt 15, in 5 the socket 14, a small quantity of wet, mushy hydraulic cement is first poured into the hole and then the bolt or pin 15 forced therein, so that when the cement sets the bolt or pin 15 is securely held in its place, 10 the cement 16 completely filling the hole and the pores of the wood, and thereby preventing water or other liquid from accumulating in the hole so as to preserve the material and prevent the bolt or pin 15 from 15 becoming loose from its anchorage in the hole.

In the adjacent ties on each side of the central tie 11, which I have designated 11', I provide a suitable recess or bored hole 17, 20 this being positioned in the tie so as to be beyond the edge of the base of the rail. Positioned in these sockets 17 are the elongated pins or bolts 18, which are of sufficient length to extend slightly above the top surface 25 face of the tie and are preferably threadless and headless. Before these pins or bolts are inserted in the sockets 17, a suitable quality of wet, mushy, hydraulic cement is poured therein and when the cement sets 30 the bolts or pins will be firmly set in the hole and the holes filled so that no water or other liquid can enter them and cause any loosening of the anchorage for the pins or bolts 18.

35 Each of the pins or bolts 18 is connected to the center or anchorage pin or bolt 15 by means of the tie or connecting rod 19, which is looped at each end, as at 20, around the exposed end of the bolt or pin 18 and 40 at an intermediate part, as at 21, around the exposed end of the pin or bolt 15, whereby the pins are all securely and firmly connected together against movement, and in view of the fact that the pin 15 extends 45 through the hole or aperture in the base of the rail, the rail itself is prevented from any movement either longitudinally or transversely, so that the track is securely held against creeping or against any movement 50 which would tend to destroy the alignment.

It is to be understood that such an anchorage construction is utilized in connection with each rail segment or section, so that the entire track is securely held and anchored 55 against creeping or other movement. In case the traffic is comparatively light in volume and the grades are not unusually heavy or steep, it is possible that the single pin 15 anchored, as shown, might be sufficient to 60 prevent the rails creeping or getting out of alignment.

It is to be noted that by inserting the pins or bolts 15 and 18 in the sockets 14 and 17, after the cement or other plastic material is 65 poured therein and driving them home, the

plastic material is subjected to pressure which forces it into the pores of the material composing the tie and out of the top of the socket so that the bolt or rod displaces an amount of plastic material equal to its 70 cubic contents. The sleeve 13 has a tight fit in the opening 12 and the bolt or rod 15 has a tight fit in the sleeve 13 when the same are first installed.

The invention can readily be laid as a part 75 of a new track and can also be installed on any track already laid and in operation. It may be applied to a track as a whole, or to any rail segment or section forming part thereof, as desired. The cost of the materials entering into the construction is not great, the construction is simple and may be readily and quickly installed at a minimum cost, which is amply warranted by the efficient results obtained by the use of this construction. This construction will give efficient results with any form of road bed construction, but it is obvious that the more securely the ties are anchored in the road, 85 the better the results. 90

Having described my invention, what I claim is:

1. In combination with a track including rails and ties, one of the rails having an aperture through its base, an element embedded 95 for anchorage in one of the ties having a projecting end immovably fixed in said aperture to prevent movement of the rail relative to the tie in any horizontal direction, additional elements embedded for anchorage 100 in the adjacent ties and removable links connecting said last mentioned anchorage elements to said first mentioned anchorage element.

2. A construction of the character specified, including in combination, a plurality of ties; a plurality of rails mounted thereon, each rail having an aperture through its base, a socket provided in the tie in alignment with said aperture and an elongated bolt securely mounted in each socket and having its projecting end passing through said aperture to prevent movement of the rail, a socket provided in each adjacent tie, an elongated bolt secured in each of said 115 sockets and having an exposed end, and a removable link member connected to the exposed end of each of said last mentioned bolts and also connected to the exposed end of said first mentioned bolt, whereby the rails are thus securely connected to the ties, so that any movement thereof relative to the ties in any horizontal direction is prevented. 110 120

3. A construction of the character specified, including in combination, a plurality of ties, a plurality of rails mounted theron, each rail having an aperture through its base, a socket provided in the tie in alignment with said aperture, an elongated headless bolt securely mounted in each socket by 125 130

having a suitable plastic substance in mushy condition in said socket before the bolt is positioned therein; the projecting end of the bolt passing through said aperture to prevent movement of the rail relative to the tie in any horizontal direction; another headless bolt driven into a tie, one on each side

of the first mentioned bolt and two links, each having an eye at each of its ends to overlie adjacent bolts. 10

In testimony whereof I hereunto subscribe my name.

JAMES DELOS NEGUS.
